SUPPORT BRACKET

James Frederick Sheetz, 3177 W. Westhaven Drive,
Anaheim, Calif. 92804

Filed June 21, 1973, Ser. No. 372,157

Term of patent 14 years

Int. Cl. D8—08

U.S. Cl. D8—242

FIG. 1

FIG. 4

FIG. 3

FIG. 2

FIG. 6

FIG. 5

FIG. 7

FIG. 1 shows a perspective view of a support bracket of my invention, broken lines being for illustrative purposes only.

FIG. 2 shows an end elevation view of the bracket along lines 2—2 of FIG. 1;

FIG. 3 shows a top plan view of the bracket along lines 3—3 of FIG. 3;

FIG. 4 shows a bottom view of the invention looking upwardly along lines 4—4 of FIG. 2;

FIG. 5 shows a side elevation view of the bracket along lines 5—5 of FIG. 1;

FIG. 6 shows a front elevation view of the bracket along lines 6—6 of FIG. 5; and

FIG. 7 shows a rear elevation view along lines 7—7 of FIG. 5.

I claim:

The ornamental design for a support bracket, substantially as shown and described.
